G. WRIGHT.
CIRCUIT PROTECTION.
APPLICATION FILED DEO. 26, 1913.

Patented July 28, 1914.

GILBERT WRIGHT,
BY *Albert S. Davis*
HIS ATTORNEY

UNITED STATES PATENT OFFICE.

GILBERT WRIGHT, OF SCHENECTADY, NEW YORK, ASSIGNOR TO GENERAL ELECTRIC COMPANY, A CORPORATION OF NEW YORK.

CIRCUIT PROTECTION.

1,105,392.

Specification of Letters Patent.

Patented July 28, 1914.

Application filed December 26, 1913. Serial No. 808,645.

To all whom it may concern:

Be it known that I, GILBERT WRIGHT, a citizen of the United States, residing at Schenectady, county of Schenectady, State of New York, have invented certain new and useful Improvements in Circuit Protection, of which the following is a specification.

My invention relates to circuit protection, its aim being to provide for the effectual interruption or disconnection of a circuit or a portion thereof upon the occurrence of abnormal conditions therein.

Among the more important advantages obtainable in connection with my invention, I may mention certainty and reliability of action; the adequate protection of extensive circuits without substantial interruption of service except in the portions or branches whence the abnormal conditions arise; and the ability to take care of the heaviest overloads or short circuits by means of simple and inexpensive apparatus. My invention is of special advantage for overload and short circuit protection in connection with lighting and power distribution circuits in the business and manufacturing sections of cities, where uninterrupted service is of the utmost importance, and I have herein described the best embodiment at present known to me with especial reference to its employment for such a purpose. While, however, the invention extends to the apparatus as shown and described and to its specific features and details, it is not confined thereto, but can be otherwise carried out and applied.

In multiple distribution systems such as above referred to, it is common to provide means for opening the circuit in various parts of the system under conditions of excessive current flow arising from overload, short circuit, or other causes. As adequate protection of the system may require the circuit to be broken automatically under currents amounting to almost the entire output of the generating plant on heavy short circuit, and as this in turn necessitates costly apparatus kept in effective condition, the means for opening the circuit usually includes a suitable overload circuit breaker for each main line (which is installed in the power house, sub-station, or other central point whence the mains radiate) and fuses in each feeder or sub-feeder branch of that line and on the premises of each current

consumer connected thereto, etc., as well as hand operated switches at various points. While in practice this arrangement usually limits the interruption of service due to abnormal conditions anywhere in the system to the main circuit on which they occur and makes the general interruption on that circuit very brief if the fuses in the feeder or branch directly involved prove effective, it is not always as satisfactory as could be wished. For example, if a consumer shunts a fuse or (as some times happens) repairs a burned-out one with a piece of copper wire, the main line circuit breaker may blow in consequence of a short circuit on his premises without his branch circuit being cut off the main line, and in this case service cannot be restored in the line until this short circuit is removed. In accordance with my invention, such difficulties are overcome by the installation of automatically operating circuit breaker means in each branch or section of the main circuit or on the premises of the circuit of each large consumer, or at other suitable points in the system. The circuit breaker means thus employed come into action under conditions of excessive current flow, but do not open till after such conditions have ceased,—whether in consequence of the opening of the main circuit breaker, the opening of a hand switch, or for any other reason,—so that the same can be made comparatively simple and inexpensive and at the same time just as effective as the main circuit breaker with which they co-act. Whenever, therefore, a main circuit breaker opens, it can be immediately closed again with the reasonable certainty that unless the trouble is on the line itself it has been cut off; and if the line is arranged in sections connected together through such circuit breaker means, trouble on a section of the line itself need not interrupt service on the sections between that one and the main circuit breaker. The accompanying drawing shows a very simple distribution circuit protected in accordance with my invention.

The circuit shown comprises the main portion 1 having in it a circuit breaker 2 of any approved type that opens in response to conditions of excessive current flow and a branch 3 derived from said main portion having in it additional circuit breaker means 4 as well as the usual protective fuse 5 for 105 110

the circuits 6, 6 of a consumer. The circuit breaker 4 comprises circuit interrupting means 7 for disconnecting the branch 3 and means 8 responsive to conditions of excessive current flow which causes the interrupting means 7 to open only after such conditions have ceased. The interrupting means 7 comprises a suitable switch blade 9 pivoted at 10, a suitably mounted contact 11, a spring 12 under whose influence the switch automatically tends to open, and a detent lever 13 fulcrumed at 14 by which opening of the switch is normally prevented. The means 8 shown includes current responsive means proper consisting of a solenoid coil 15 connected in the circuit 3 and a core part 16 associated therewith,—which latter at the proper time acts to trip and render ineffective the detent 13 and so serves as the operating means for the switch 7. The operative connection through which this is effected is at the proper time formed by the engagement of a conical head or catch 17 on the core part 16 with a latch 18 pivoted to the detent 13 at 19; normally, however, the core 16 and the catch 17 occupy the lowermost, inoperative positions in which they are shown, with the catch 17 out of engagement with the latch 18 so that the core 16 is not in immediately operative connection therewith and is incapable of actuating the switch 7. Preferably the solenoid 15 is so designed—with or without regard to the normal loads on the main portion 1 of the circuit—that it will not be able to raise its core 16 except when the current in said branch 3 is so strong that opening of the main circuit breaker 2 would result. If it is desired that the circuit breaker 4 should not open on momentary overload, or unless the circuit breaker 2 opens, or ahead of the circuit breaker 2 in the event of the current falling off before the latter actually opens, a suitable dashpot 20 may be connected to the core 16; and similar means, may, if necessary, be employed in connection with the circuit breaker 2 to insure that the catch 17 shall pass the latch 18 before said circuit breaker 2 opens, etc.

50 The operation is as follows: If an overload occurs on the circuit 6, the fuse 5 may be able to take care of it and effectually cut off the branch 3 before the current becomes strong enough to open the main circuit breaker 2. If, however, the current becomes so heavy that an arc forms between the terminals of the fuse 5, or if the fuse for any other reason fails to cut off the branch 3, the field of the solenoid 15 will 55 become strong enough to raise the core 16 till the catch 17 trips past the latch 18 into operative position with reference thereto, thus establishing an operative connection between the detent 13 and the core 16 and rendering the latter capable of actuating the switch 7. As long as the excessive current flow continues, the core 16 will be sustained in its elevated position and opening of the switch 7 will still be prevented; but as soon as the circuit is effectually broken by the opening of the main circuit breaker 2,—which will happen almost instantly,—the core 16 will drop and operate on the latch 18 to trip open the switch 7. As this will also occur almost instantaneously, the circuit breaker 2 can be closed practically as soon as it opens and service on the other feeders or branches of the main 1 maintained without any material interruption,—the circuit breaker 4 remaining open until locally reset.

55 For the sake of simplicity of illustration, only a single wire circuit is shown in the drawing,—the return wires being omitted or replaced by grounds,—but it will be understood that my invention can be applied to circuits of all sorts and that connection through any or all of the conductors of the circuit can be interrupted by the circuit breakers 2 and 4. It is also to be understood, of course, that my invention is applicable to alternating or pulsating current circuits as well as to those carrying continuous, uniform, unidirectional current, and that transformers, converters, etc., may be interposed in the circuits as desired.

60 What I claim as new and desire to secure by Letters Patent of the United States, is:—

1. In an electric circuit, the combination with circuit interrupting means therefor, of means responsive to conditions of excessive current flow therein for causing said circuit interrupting means to open after such conditions have ceased. 100
2. In an electric circuit, the combination of circuit interrupting means, operating means for said circuit interrupting means not ordinarily capable of actuating the same, and means responsive to conditions of excessive current flow for rendering said operating means capable of actuating said circuit interrupting means and for preventing opening of the latter during the continuance of such conditions. 110
3. In an electric circuit, the combination of a circuit breaker for opening the circuit under conditions of excessive current flow and additional circuit breaker means that comes into action under like conditions but opens only after such conditions have ceased. 115
4. In an electric circuit comprising a main portion and a branch derived therefrom, the combination of means in the main portion for opening the circuit under conditions of excessive current flow and circuit breaker means in the branch responsive to like conditions therein which opens after the means first mentioned has effectually broken the circuit. 125
5. In an electric circuit comprising a main portion and a branch derived therefrom, the combination of means in the main portion for opening the circuit under conditions of excessive current flow and circuit breaker means in the branch responsive to like conditions therein which opens after the means first mentioned has effectually broken the circuit. 130

portion and a branch derived therefrom, the combination of a circuit breaker in the main portion responsive to conditions of excessive current flow and circuit breaker means in the branch responsive only to current flow heavy enough to bring about the opening of said first mentioned circuit breaker that opens after the first mentioned circuit breaker has effectually broken the circuit and remains open when the first mentioned circuit breaker is closed again, so that the branch remains effectually cut off.

6. In an electric circuit comprising a main portion and a branch derived therefrom, the combination of a circuit breaker in the main portion responsive to conditions of excessive current flow therein, circuit interrupting means in the branch, and means responsive to conditions of excessive current flow in the branch which causes said circuit interrupting means to open after such conditions have ceased.

7. In an electric circuit, the combination of means for opening the circuit under conditions of excessive current flow, additional circuit interrupting means that automatically tends to open and means for normally preventing such opening, means for rendering said last mentioned means ineffectual normally not in immediately operative con-

nection therewith, and means for establishing such operative connection under conditions of excessive current flow in said circuit and for preventing opening of said circuit interrupting means during the continuance 35 of such conditions.

8. In an electric circuit, the combination of a circuit breaker responsive to conditions of excessive current flow, additional circuit interrupting means that automatically tends 40 to open, a detent for normally preventing such opening, a latch adapted to serve as an operative connection for releasing said detent, a catch adapted to engage and operate on said latch which tends to occupy an inoperative position out of engagement therewith, and electromotive means operating under conditions of excessive current flow in the circuit for moving said catch past said latch into operative position with reference 50 thereto so that said detent may be tripped when the circuit is broken by the opening of said circuit breaker.

In witness whereof, I have hereunto set my hand this 24th day of December, 1913. 55

GILBERT WRIGHT.
